UNITED STATES PATENT OFFICE.

MILLER REESE HUTCHISON, OF UPPER MONTCLAIR, NEW JERSEY, ASSIGNOR,
BY MESNE ASSIGNMENTS, TO HUTCHISON ACOUSTIC COMPANY, A COR-
PORATION OF NEW JERSEY.

TELEPHONIC APPARATUS.

SPECIFICATION forming part of Letters Patent No. 737,242, dated August 25, 1903.

Application filed April 11, 1902. Serial No. 102,338. (No model.)

To all whom it may concern:

Be it known that I, MILLER REESE HUTCHISON, a citizen of the United States, residing at Upper Montclair, in the county of Essex and 5 State of New Jersey, have invented certain new and useful Improvements in Telephonic Apparatus, of which the following is a full, clear, and exact description.

This invention is a portable telephonic apparatus intended to be used by persons with impaired hearing; and it consists of a box or casing containing a telephone transmitter and receiver, a battery, and suitable switching devices, the casing being constructed to 10 coöperate with the transmitter in a manner to collect sounds and concentrate them upon the diaphragm of the transmitter, whereby the entire apparatus is adapted to be used in a room or hall to enable partially-deaf persons to hear speech, music, or other sounds which are ordinarily heard by persons with 15 normal hearing powers. The apparatus is furthermore devised to be of simple and compact construction and easily and quickly manipulated.

In the accompanying drawings, Figure 1 is a perspective view of the improved apparatus. Fig. 2 is a horizontal section thereof, and Fig. 3 is a vertical longitudinal section 20 showing the interior mechanism in elevation.

The telephonic apparatus is inclosed in a rectangular box A, two opposite sides of which, a and a', are hinged to the rear wall b of the box, so that they can be swung outward laterally when desired. The box is provided with a false bottom c, forming a space c', in which is located a lever d, pivoted at d' and extending through a slot d² in the front wall of the case, where it is provided with a handle d³. The slot contains notches d⁴, into any one of which the lever can be set to hold it in position. At equal distances each side of the pivot d' links e and e' are respectively connected and extend thence to the respective walls of the box a and a'. Thus when the handle is moved through the slot the said walls are caused to either open or close, depending upon the direction of movement of the handle. Parallel to each of the closed

side walls a and a' are partitions f and f', 50 which, together with the remaining walls of the box, form an inclosure in the forward end of which are located a number of batteries g and immediately back of these a tilting support or table h and back of this a telephone-transmitter T. The transmitter is of cylindrical shape, containing the usual diaphragm and the electrodes (not shown) and is in this instance mounted to rotate upon the small ends of two sound-conducting funnels 60 i and i', the funnels being fixed at their larger ends to the respective partitions f and f', said partitions having concentric circular openings leading into the funnels. The said openings are located near the hinges of the 65 walls a' or at the apexes of the triangular space formed by said walls when they are open. To the transmitter is fixed a concentric pinion t, which is connected by a gear-segment l on the end of a lever l', which carries the support h. This lever is pivoted to the bracket o and has attached to it a spring s, which tends to swing it on its pivot. On the rim of the transmitter is a pin p, which is adapted to be brought forcibly into contact with a stop p' when the transmitter is rotated, as will be hereinafter described. The support h is adapted to carry a telephone-receiver R, the weight of which is sufficient to 70 overcome the spring s, and thus hold the parts 75 in the position shown in Fig. 3. This telephone-receiver is supposed to be connected in circuit with the transmitter and a battery in the usual manner, the circuits not being here shown in detail. In the top of the box 80 is a small hinged cover a², through which the receiver can be reached and removed from the box for use. The pin p may be used in connection with the stop p' as an electrical switch or cut-out to throw the instruments 85 into and out of circuit with the battery g.

The apparatus is to be used as follows: The box being small and light can be carried to any place desired by the person using it, such as a place of amusement or to the house of a friend. It may, in fact, be used at any place where the possessor may be. The sides of the box are thrown open by moving the han-

dle d^3 to any point desired, the open triangular space thus formed being then directed toward the source of sound—such, for instance, as toward the stage at a theater or other place 5 of amusement. The telephone-receiver is then lifted from the box, whereupon the lever l' , being relieved of its weight, is swung on its pivot by the spring s . This rotates the transmitter through about a half-turn by reason of 10 the engagement between the segment and the pinion, the rotation being stopped by the pin engaging with the stop p . The rotary motion of the transmitter and the shock which it sustains when the pin strikes the stop are sufficient 15 to loosen the granular electrodes of the transmitter and put it into good working condition. At the same time if the pin and stop are used as a switch the instruments are put into circuit with the battery and become operative 20 at once. Sounds approaching the apparatus enter the triangular spaces formed by the open side walls and are deflected laterally and inwardly through the openings in the partitions $f f'$, through the funnels $i i'$ to the diaphragm or diaphragms of the transmitter, 25 which transmits them over the circuit to the receiver held at the ear of the user of the apparatus.

Good results can be obtained under certain 30 conditions without opening the sides of the box in the manner described by uncovering the funnels by opening the small doors a^3 .

Having described my invention, I claim—

1. A box or casing, a telephone transmitter, 35 receiver and battery adapted to be housed

therein, said box or casing having a movable wall adapted to receive sounds from an external source and direct them to the housed transmitter, substantially as described.

2. A box or casing, a telephone-transmitter 40 therein, two opposite walls of said box being hinged and adapted when open to direct sounds to the transmitter.

3. A sound-collecting device, consisting of a box having movable, converging sides, in 45 combination with a telephone-transmitter contained in said box the sides when open forming a passage to direct sounds to the transmitter.

4. A box or casing, in combination with a 50 telephone-transmitter therein, the box provided with two hinged walls, a system of levers connecting with said walls whereby the movement of one wall will cause the movement in the opposite direction of the other, 55 the angular position of the walls serving to direct sounds to the transmitter, substantially as described.

5. A box or casing, provided with openings 60 in two of its sides, a telephone-transmitter in line with said openings, hinged walls of said box or casing opposite said openings whereby sounds will be directed by said hinged walls through the opening to the transmitter.

In witness whereof I subscribe my signature in presence of two witnesses.

MILLER REESE HUTCHISON.
